(57) **CLAIM**

The ornamental design for a snowman candle, as shown and described.

DESCRIPTION

FIG. 1 is a front elevational view of a snowman candle showing our new design;

FIG. 2 is a rear elevational view thereof;

FIG. 3 is a right-side elevational view thereof;

FIG. 4 is a left-side elevational view thereof;

FIG. 5 is a top view thereof; and,

FIG. 6 is a bottom view thereof.

The broken line showing the outline of the snowman arms is for illustrative purposes only and forms no part of the claimed design.
